UNITED STATES PATENT OFFICE.

HIDEJI KATAKAWA AND KOKICHI MAEJIMA, OF NEW YORK, N. Y.

DESIGN FOR AN INCENSE-BURNER.

52,322.

Specification for Design.

Patented Aug. 27, 1918.

Application filed May 20, 1918. Serial No. 235,739. Term of patent 3½ years.

To all whom it may concern:

Be it known that we, HIDEJI KATAKAWA and KOKICHI MAEJIMA, subjects of the Emperor of Japan, residing at New York, in the county of New York and State of New York, have invented a new, original, and ornamental Design for Incense-Burners, of which the following is a specification, reference being had to the accompanying drawing, form part thereof.

In the drawing, the figure is a perspective view of the incense burner.

We claim:—

The ornamental design for an incense burner as shown.

HIDEJI KATAKAWA.
KOKICHI MAEJIMA.

Witnesses:

JAMES A. KOEHL,
A. V. DOYLE.
